US00D420979S

United States Patent [19]

Chang

[11] Patent Number: Des. 420,979

[45] Date of Patent: ** Feb. 22, 2000

[54] ELECTRICAL CONNECTOR

[75] Inventor: Jen-Jou Chang, Yung-Ho, Taiwan

[73] Assignee: Hon Hai Precision Ind. Co., Ltd.,
Taipei Hsien, Taiwan

[**] Term: 14 Years

[21] Appl. No.: 29/103,292

[22] Filed: Apr. 12, 1999

[30] Foreign Application Priority Data

Oct. 13, 1998 [TW] Taiwan 85302219

[51] LOC (7) Cl. 13-03

[52] U.S. Cl. D13/146; D13/147

[58] Field of Search D13/133, 146,
D13/147; D14/256; 439/63, 532, 536, 540.1,
541.5, 939, 639, 607
